US00D874506S

(12) **United States Design Patent** (10) **Patent No.:** **US D874,506 S**
(45) **Date of Patent:** ** *Feb. 4, 2020

(54) **DISPLAY SCREEN OR PORTION THEREOF
WITH GRAPHICAL USER INTERFACE**

(71) Applicant: **SAMSUNG ELECTRONICS CO., LTD.**, Suwon-si, Gyeonggi-do (KR)

(72) Inventors: **Byung-Jin Kang**, Seoul (KR); **Ji-Hyun Choi**, Seoul (KR); **Kyu-Hong Kim**, Yongin-si (KR); **Gwan-Young Yoo**, Ahnsan-si (KR); **Do-Hyung Lee**, Yongin-si (KR); **Yu-Sun Cheong**, Seoungnam-si (KR); **Byeong-Seok Choi**, Yongin-Si (KR)

(73) Assignee: **SAMSUNG ELECTRONICS CO., LTD.**, Gyeonggi-Do (KR)

(*) Notice: This patent is subject to a terminal disclaimer.

(**) Term: **15 Years**

(21) Appl. No.: **29/626,171**

(22) Filed: **Nov. 15, 2017**

Related U.S. Application Data

(63) Continuation of application No. 29/559,851, filed on Mar. 31, 2016.

(57) **CLAIM**

The ornamental design for a display screen or portion thereof with graphical user interface, as shown and described.

DESCRIPTION

The FIGURE is a front view of a display screen or portion thereof with graphical user interface, showing our new design.

The broken lines illustrate the display screen or portion thereof and the remainder of the graphical user interface, and form no part of the claimed design.
